 Alma, Mich., a corporation of Michigan

Application November 19, 1934, Serial No. 753,710

6 Claims. (Cl. 153—25)

This invention relates to presses and particularly to presses for shaping short cylindrical hoop-like members of ductile metal into annular elements suitable for use as rims for bicycle wheels 5 or for analogous purposes.

Heretofore metallic bicycle rims have generally been formed by subjecting a flat band of ductile metal to a rolling operation, the band being passed endwise into and through a rolling mill in which it is given the desired cross-sectional shape and approximately a circular form, the ends of the band being thereafter welded together. I have discovered that a superior bicycle rim may be formed by first securing the ends of 10 a flat metallic band together, as by a welding operation, to form a short cylindrical blank and thereafter subjecting this short cylindrical blank to shaping operations whereby its margins are outwardly stretched and the rim is given the desired cross-section. A rim formed in this manner 15 is stronger and has less tendency to warp or get out of shape than rims formed upon previously known means and is also superior in appearance.

For the purpose of stretching the marginal portions of the blank and giving these margins the desired cross-sectional shape, a novel form of press has been devised, which press comprises the subject matter of the present application and will be hereinafter described in detail. The principles 20 of the invention may be employed in presses designed for the manufacture of articles other than bicycle rims, and hence, as will be appreciated by one skilled in the art, the design and arrangement of the component elements of the invention may 25 be considerably varied without departing from the import thereof. The embodiment of the invention which will be hereinafter described in detail and illustrated in the accompanying drawing is therefore set forth by way of example only.

40 In the drawing:

Figure 1 illustrates the press in plan view, portions being broken away;

Figure 2 is an axial section through the press, the parts being shown in the positions which they 45 occupy just prior to the pressing operation;

Figure 3 is a similar view but showing the parts in the positions which they occupy at the completion of a pressing operation;

Figures 4 and 5 are partial axial sections 50 through the press, the shapes of several of the press elements, however, having been modified in order to perform further shaping operations upon the blank; and

Figure 6 illustrates in section the original blank, 55 the blank after one pressing operation has been

performed, and the blank after the final pressing operation has been performed.

The press comprises essentially a base indicated at 10, which may conveniently be in the form of a disc, an annular lower die member 11 resting upon the base, a disc-like upper die member 12 which may if desired be attached to the upper plate of a power press of known character, an intermediate disc 13 carrying an expanding blank-gripping means generally indicated at 14, and an outer confining ring indicated at 15. The lower and upper die members 11 and 12 are provided with blank engaging and shaping surfaces 11' and 12' respectively, and the confining ring, which is formed in two annular portions normally 10 spaced apart by yielding elements or springs 16, is provided with complementary blank engaging and shaping surfaces 15' and 15². The short cylindrical ductile blank, which is indicated at 17, is adapted to have its upper margin engaged 15 by and shaped between the complementary surfaces 12' and 15' of the press, the complementary surfaces 11' and 15² of the press cooperating in the shaping and expanding of the lower margin 20 of the blank when the press is actuated. As shown, the blank engaging surface 11' of the lower die 11 is generally conical in shape, and the blank engaging surface 12' of the upper die 12 is of the same shape so that, as the dies are 25 caused to approach each other in the operation 30 of the press, the margins of the blank 17 are wedged or stretched outwardly.

The interior blank engaging means 14 comprises a series of generally segmental plates 20 having radial edges and curved outer ends so as 35 to fit closely against the inner wall surface of the blank. These segments are slidably mounted upon the upper surface of disc 13, bolts 21 having their lower ends secured in disc 13 which passes through radial slots formed in the segmental plates, and the heads of these bolts serving as means for preventing upward displacement of the plates respectively. To the inner end of each plate is connected the outer end of a toggle link 22, and the inner ends of these toggle 45 links are in turn pivotally connected to a central disc 23 fixed upon the upper end of a shaft 24 which projects downwardly through central apertures formed in the intermediate disc 13 and the base 10 respectively. By rotating the shaft 24 in 50 one direction, the disc 23 is also caused to rotate and hence to swing the inner ends of the toggle levers 22 circumferentially of the press.

In Figure 1 two positions of one of the toggle levers are indicated by full and dotted lines. 55

When this toggle lever is in its full-line position, the segment 14 to which it is connected is inwardly spaced from the surface of the blank 17, as clearly indicated in Figure 2, and when the 5 toggle lever is moved to its dotted-line position, the segment is thrust outwardly to the position shown in dotted lines in Figure 1 and the curved outer edge of the segment is in tight engagement with the inner cylindrical surface of 10 the blank at a point midway between its edges. Naturally all of the toggles operate simultaneously as shaft 24 is rotated, and hence the blank is simultaneously engaged by and disengaged from the various segments 20. Disc 13 is normally 15 maintained in the position in which it is shown in Figure 2, yieldable elements 25 being provided for normally maintaining the disc in this position while at the same time permitting movement of the disc toward the base 10 when pressure is applied in the operation of the press.

For convenience in assembly, the confining ring 15 is formed in two sections, the ends of which are releasably connected together by latching devices of any desired type, such as indicated 25 at 26 in Figure 1. For the further convenience of the operator in manipulating the confining ring, each of the two sections thereof is jointed at a mid-point, hinges 27 being provided at these 30 points to permit relative movement of the two parts thus joined, as indicated in dotted lines in Figure 1.

In operating the press shown in Figures 1, 2, and 3, a short cylindrical blank of ductile metal is first positioned as shown in Figure 2 with its 35 edges equidistantly spaced from the segmental gripping and securing device 14. The shaft 23 is then rotated to simultaneously rock all of the toggle members 22 and to thrust outwardly the sections 20 of the internal gripping device, the 40 curved outer edges of these sections frictionally gripping the inner surface of the blank. The swinging movement of each of the toggles 22 is carried, in thus expanding the securing plate 14, slightly beyond a truly radial position, and a 45 positive stop for the operating shaft 24 is provided to prevent further rotation. The toggles are thus locked in position with the plate 14 expanded. Thereafter pressure is applied to the upper die 12 and the base 10 to cause these 50 members to approach each other, whereupon the co-operating blank engaging and shaping surfaces of the upper and lower die members and the confining ring 15 cooperate in expanding and shaping the upper and lower margins of the blank.

55 At the conclusion of the operating stroke of the press, the parts occupy the positions in which they are shown in Figure 3, the upper and lower surfaces of the die members being in close contact with the outer edges of segments 20, the 60 upper and lower sections of the confining ring 15 pressed into close contact, the supporting ring 30 for the confining ring lowered into contact with the upper surface of base 10, and the confining ring supporting springs 31 being compressed. As the dies are closed, the upper and lower margins of the blank are outwardly stretched, the metal being stretched beyond its 65 elastic limit so as to retain a permanent set. As a result of this operation the blank has been 70 caused to assume in section the shape shown in the intermediate illustration in Figure 6.

For the purpose of further shaping the blank so that it is caused to assume in cross-section the shape shown in the right-hand portion of 75 Figure 6, the blank engaging and shaping ele-

ments of the press are changed, the shoulder blank engaging elements indicated in Figures 4 and 5 being substituted for those corresponding elements having the more gently curved blank engaging surfaces shown in Figures 2 and 3. As 5 will be seen from an inspection of Figures 4 and 5, the substituted parts retain the same relative positions as before, but the confining ring 33 is formed in one piece and its blank engaging surfaces 33' and 33² are rather sharply curved as 10 shown. The blank engaging surface 34' of the upper die member and the blank engaging surface 35' of the lower die member 35 are correspondingly shaped. The substituted confining ring 33 may be formed in one instead of two 15 pieces, as shown. After closing of the press including the modified blank engaging members, the blank is removed and passed on to other fabricating machines for subsequent operations, as for instance spinning and curving of its outer 20 edges, perforations for spoke receiving sleeves, etc.

As has been previously pointed out, in shaping short cylindrical ductile metallic members or blanks for other purposes, the design of the 25 cooperating shaping members may be further modified without departure from the invention, and also the exact arrangement of the parts may be considerably varied in adapting the invention for the shaping of blanks of various types. 30

Having thus described the invention, what is claimed as new and desired to be secured by Letters Patent is:

1. A press for uniformly expanding the margins of short continuous cylindrical blanks of 35 ductile metal comprising means for frictionally gripping the inner surface of the blank intermediate the edges thereof to secure the same in position to be acted upon, upper and lower dies relatively movable toward each other along 40 the axis of the blank and having generally conical blank engaging and shaping surfaces adapted to engage the inner wall surfaces of the margins of the blank when so moved to outwardly deflect such margins by stretching the metal thereof, 45 and an annular confining die adapted to encircle the blank and having spaced blank engaging surfaces adapted to cooperate respectively with the blank engaging surfaces of the upper and lower dies. 50

2. A press for uniformly expanding the margins of short continuous cylindrical blanks of 55 ductile metal comprising means for frictionally gripping the inner surface of the blank midway between the edges thereof to secure the same in position to be acted upon, and means movable axially of the blank for outwardly deflecting and shaping the marginal portions of the blank by stretching the metal thereof.

3. A press for uniformly expanding the margins of short continuous cylindrical blanks of 60 ductile metal comprising means for frictionally gripping the inner surface of the blank midway between the edges of the same to frictionally hold the blank in position to be acted upon, confining means encircling the blank and engaging the outer wall thereof midway between the edges, and means movable axially of the blank for outwardly deflecting and shaping the marginal portions of the blank by stretching the metal thereof. 65

4. The combination set forth in claim 3 in which the confining means comprises two similar annular members and yieldable elements normally maintaining the same in spaced relation- 70 75

ship, said elements being compressible by said deflecting and shaping means.

5. The combination set forth in claim 3 in which the gripping means comprises a plurality of segmental plates and mechanism for simultaneously moving said plates outwardly or inwardly as desired.

6. The combination set forth in claim 3 in which the gripping means comprises a plurality of segmental plates and mechanism for simultaneously moving said plates outwardly to blank engaging position, locking them in such position, or retracting the same as desired.
